(57) CLAIM

The ornamental design for an extendable face cradle, as shown and described.

DESCRIPTION

FIG. 1 is a perspective view of an extendable face cradle showing my new design, shown in an extended position; FIG. 2 is a left side elevation view thereof, the right side elevation view being a mirror image thereof;

FIG. 3 is a front elevation view thereof;

FIG. 4 is a rear elevation view thereof;

FIG. 5 is a top plan view thereof;

FIG. 6 is a bottom plan view thereof;

FIG. 7 is a perspective view thereof, shown in a folded position; and,

FIG. 8 is a left side elevation view thereof.

The broken lines shown in the drawings depict environmental structure that forms no part of the claimed design.

1 Claim, 6 Drawing Sheets
